UNITED STATES PATENT OFFICE.

JAMES ARRANCE, OF ALLENTOWN, PENNSYLVANIA.

LOW-WATER ALARM.

SPECIFICATION forming part of Letters Patent No. 745,987, dated December 8, 1908.

Application filed December 19, 1902. Serial No. 135,930. (No model.)

To all whom it may concern:

Be it known that I, JAMES ARRANCE, a citizen of the United States, residing at Allentown, in the county of Lehigh and State of Pennsylvania, have invented a new and useful Low-Water Alarm, of which the following is a specification.

My invention relates to low-water alarms for steam-boilers, and has for its objects to produce a device of this character in which the construction is materially simplified, the alarm is sounded directly from the boiler, and the operation of the device to sound the alarm occurs immediately and without failure upon the water in the boiler reaching the danger-point.

The invention consists in the details of construction more fully hereinafter pointed out.

In the accompanying drawings, Figure 1 is a side elevation, partly in section, of my improved device, showing the valve closed. Fig. 2 is a similar view with the valve open.

Referring to the drawings, 1 indicates a steam-boiler, and 2 a vertical chamber mounted and suitably supported adjacent thereto.

I preferably provide this chamber with a removable cover 3, bolted securely thereon, and with a removable bottom 4, also secured by bolts.

5 5 is a water conduit or pipe connecting the boiler and chamber preferably a short distance below the low-water or danger line of the boiler. This conduit is adapted to conduct water from the boiler to the chamber to 35 control the movements of a float 6, mounted in the chamber and adapted for vertical movement therein.

7 is a steam whistle or alarm preferably mounted above the chamber 2 and connected 40 directly with the steam-boiler above the water-line by a steam conduit or pipe 8.

9 is a valve-casing preferably cast directly onto the top of the chamber and suitably formed in its interior with a valve-seat 10. 45 The steam-pipe 8 is coupled to one end of the valve-casing, while a short pipe 11, leading to the whistle, is coupled to its opposite end. The whole forms, in effect, a continuous conduit connecting the whistle directly with the 50 boiler, as above stated.

12 is a valve mounted in the valve-casing and connected to the top of float 6, the move-

ments of which cause it to close against or be retracted from the valve-seat 10 to control the admission of steam to the whistle. The valve 55 is provided with a head 13, enlarged at its bottom to prevent its escape from the valve-casing and permitting it to sustain the weight of the float when it drops. The valve-head is beveled at its top and projects upward through 60 the valve-seat in such position that the steam will impinge upon the same and assist in forcing the valve downward when the water in the boiler falls to the danger-line.

14 and 15 are stop-cocks mounted, respectively, in the steam and water conduits for closing either or both at will.

16 is a valve-controlled discharge or drain pipe in the bottom of the chamber, and 17 is a similar pipe in the bottom of the float for 70 discharging any water that might possibly enter the same.

17 is a pipe which connects the chamber 2, near its upper end, with the boiler at a point above the water-line of the latter to insure 75 equalization of the pressure in the chamber above and below the float 6, as usual.

18 indicates an ordinary glass gage-tube which permits inspection from time to time of the state of the water within the chamber 80 2, this tube being partially surrounded by a metal protecting-easing 19.

In operation, supposing the water in the boiler to be at a safe level, the float will be buoyed up by the water in the chamber and 85 the parts will occupy the position shown in Fig. 1, with the valve closed. Should the water in the boiler fall to the danger-line, which is, as indicated in the drawings, just below the float, the float will immediately 90 drop to the water-level, retract the valve, and permit the steam to flow to the whistle and sound the alarm.

It will be seen that in my device there is a direct connection between the boiler and whistle, through which the steam travels direct and not indirectly through an intermediate chamber, thus insuring the immediate and perfect operation of the device.

Having thus described my invention, what 100 I claim is—

1. The combination with a steam-boiler, of a chamber situated adjacent thereto, a float mounted in the chamber, a water-conduit

leading from the boiler to the chamber and adapted to conduct water to the chamber to control the movement of the float, an alarm, a steam-conduit connecting the alarm directly with the boiler, a valve-seat mounted in the steam-conduit, and a valve adapted to close upon the seat and having a vertically-disposed stem tapped directly into the upper end of the float, said valve projecting through the seat in position to be impinged upon by the steam.

2. The combination with a steam-boiler, of a chamber situated adjacent thereto and having a removable cover, a valve-casing formed integral with the cover and provided with a valve-seat, a float located within the chamber, a valve adapted to close upon the valve-seat and project through the same and having a vertically-disposed stem tapped at its lower end into the upper end of the float, a water-

conduit leading from the boiler to the chamber to conduct water to the latter for operating the float, a pipe tapped into the valve-casing at one side of the valve and having a whistle associated therewith, and a steam-pipe tapped into the valve-casing at the other side of the valve and connected with the steam-boiler and adapted to conduct steam directly from the boiler to the whistle, said steam in its passage being adapted to impinge upon the valve, whereby the movement of the float for opening the same will be assisted by the pressure of the steam on the valve. 25

In testimony that I claim the foregoing as my own I have hereto affixed my signature in 30 the presence of two witnesses.

JAMES ARRANCE.
